APPARATUS FOR SAMPLING WOOL AND
OTHER FIBERS
Herbert J. Wollner, Belmont, Mass., assignor to ACH
Fiber Service, Inc., Boston, Mass., a corporation of
Massachusetts
Filed May 9, 1960, Ser. No. 27,892
2 Claims. (Cl. 73—423)

In evaluating wool it is customary to take representative samples from various bags or bales of a consignment and to test these samples for foreign matter, grease content, etc. The samples are taken by boring cores out of bales or bags of wool and then extracting the cores from the boring tools. In the case of densely packed wool, as in most bales, the wool is dense enough to be bored with a small tool of the order of $\frac{1}{2}$ inch in diameter. However in the case of relatively loose wool in bags and the like it is necessary to use larger tools of the order of 2 and $1\frac{1}{2}$ inches in diameter. In any case cores from a large number of bags or bales involve considerable bulk, whereas only a small amount of wool would serve the purpose if it comprised the average of all of the bales or bags. Heretofore, owing to the nature of wool, it has not been possible to mix wool like ore, coal, etc. to get a homogeneous average without the use of relatively massive machinery. Consequently it has not been feasible to obtain a small sample of wool which reliably constitutes the average of a large number of bales or bags except by the laborious process of transporting a large sample and mixing it with heavy duty equipment. Not only does this represent a waste of wool in the sampling process but in cases where the testing laboratory is at a location remote from the place where the wool is stored it also represents a transportation problem. If a small average sample could be obtained readily, it could be sent by air to a remote laboratory in a short time and at small cost. Thus a few laboratories could serve large areas.

Objects of the present invention are to produce apparatus for quickly and easily obtaining a small sample of wool which is truly representative of a large number of bales or bags, to obtain such a sample quickly and easily, and generally to improve the art of sampling wool and similar materials.

According to the present invention the apparatus comprises a compression chamber having an opening through which material may be introduced, means for compressing the material against one side of the chamber which has an aperture, together with a coring tool fitting the aperture and means for reciprocating the tool in the aperture to extract a sample core from the compressed material. Preferably the aforesaid side has a plurality of apertures with one of the boring tools in each aperture, and means to reciprocate the tools conjointly. The compressing means preferably comprises a ram extending through the opposite side of the chamber. In the preferred embodiment the apparatus comprises an ejector behind each tool in alignment therewith for ejecting the core on the backward movement of the tool.

By taking a small sample of wool or the like from each of a number of batches and compressing the samples together as aforesaid, it is possible to obtain small samples which are truly representative of the average quality of a number of bales or bags.

2

For the purpose of illustration a typical embodiment of the invention is shown in the accompanying drawings in which—

FIG. 1 is a side view with parts broken away;
FIG. 2 is a section of line 2—2 of FIG. 1;

FIG. 3 is a longitudinal central section of one of the coring tools with one of the aforesaid ejectors therein;

FIG. 4 is a longitudinal section of a modified coring tool; and

FIG. 5 is a section on line 5—5 of FIG. 1.

The particular embodiment of the invention chosen for the purpose of illustration comprises a table 1 having an opening 2 to receive a bag 3 for the samples of wool or the like. Mounted on table 1 is a compression chamber 4 having a door 6 through which the chamber may be charged with samples of material, the door being held in closed position by means of a latch 7 hooking over a pin 8 on the door. Reciprocating lengthwise of the chamber 4 is a ram 9 having a piston sliding in a cylinder 11 with rods 12 to guide the back and forth movement of the piston. The cylinder 11 has the usual connections 13 and 14 by which the piston may be operated with compressed air or hydraulic fluid. The opposite end of the chamber 4 is provided with a plurality of apertures 16 through which the coring tools 17 may be moved back and forth to extract the samples of the compressed material. The tools 17 are actuated by means of a piston reciprocating in the cylinder 18 having the usual connections 19 and 21 for hydraulic fluid or the like. The tools 17 are fast to a head 22 mounted on the end of the piston rod 23. Fast to the stationary head 24 are ejector rods 26 for ejecting the cores from the coring tools.

In operation the door 6 is opened to charge the chamber 4 with samples of material. After the door is closed and latched the plunger 9 is advanced to compress the wool against the apertured end of the chamber. Then the coring tools are advanced through the apertures 16 to extract cores of material and then retracted to the position shown in FIG. 1. As they are retracted the cores 25 C are ejected from the tools by the ejectors 26 as illustrated in FIG. 3. As shown in FIG. 4 the coring tool 17 may be tapered toward the cutting ends.

It should be understood that the present disclosure is for the purpose of illustration only and that this invention includes all modifications and equivalents which fall within the scope of the appended claims.

I claim:

1. A machine for extracting cores from a batch of compressible material comprising a compression chamber having an opening through which material may be introduced, means for compressing the material against one side of the chamber, said side having a plurality of apertures, a coring tool fitting each aperture, a reciprocating head supporting the rear ends of the tools, the head having openings coaxial with the tools respectively, a stationary support behind said head, ejectors mounted on said support to extend through said head into the tools respectively, and means for reciprocating said head 50 toward and from said side between a retracted position in which said coring tools are withdrawn from said openings and said ejectors extend through the tools and an advanced position in which the tools extend through the openings into said chamber, said last means including a

plunger extending through said support in offset relation to said ejectors.

2. A machine for extracting cores from a batch of compressible material comprising a compression chamber having an opening through which material may be introduced, means for compressing the material against one side of the chamber, said side having an aperture, a coring tool fitting said aperture, a reciprocating head supporting the rear end of the tool, the head having an opening coaxial with the tool, a stationary support behind said head, an ejector mounted on said support to extend through said head into the tool, and means for reciprocating said head toward and from said side between a re-

tracted position in which said coring tool is withdrawn from said opening and said ejector extends through the tool and an advanced position in which the tool extends through the opening into said chamber.
